UNITED STATES PATENT OFFICE.

FREDERICK C. HOLKUM, OF POCOHONTAS, ILLINOIS.

MATCH-BOX.

1,021,602.

Specification of Letters Patent. Patented Mar. 26, 1912.

Application filed May 10, 1911. Serial No. 626,211.

To all whom it may concern:

Be it known that I, FREDERICK C. HOLKUM, a citizen of the United States, residing at Pocahontas, in the county of Bond and State of Illinois, have invented new and useful Improvements in Match-Boxes, of which the following is a specification.

This invention relates to match boxes, and has for an object to provide dispensing means therefor, whereby a single match can be discharged from the box and conveyed to a presenting trough where it can be conveniently grasped by the operator.

In the drawing, forming a portion of this specification and in which like numerals of reference indicate similar parts in the several views:—Figure 1 is a front view of the box. Fig. 2 is a section therethrough on the line 2—2 of Fig. 1. Fig. 3 is a view similar to Fig. 2 showing a slightly modified form of the invention.

Upon reference to Figs. 1 and 2 of the drawing, it will be seen that the box 1 embodies a casing 2 having a front wall 3, a rear wall 4, a top 5 and end walls 6, the wall 4 having a filling opening therein by means of which the casing can be filled with matches. This opening is closed by a suitable cover 7.

The match dispensing or feeding means includes a shaft 8 which is journaled in the end walls of the casing, one end of said shaft being provided with a manipulating knob 9. Spaced disks 10 are secured to the shaft, and as illustrated, each disk has peripheral notches 11 therein, the notches of one disk being disposed in line with the notches of the adjacent companion disk. A combined dividing and directing member 12 is located in the casing, being preferably of concavo-convex form, and concentrically arranged with respect to the disks 10 and suitably spaced therefrom to permit the disks to be freely rotated in either direction. This member has its opposite side walls 12' extending downwardly toward the bottom of the casing and then inwardly, at 13, toward the shaft 8 to form deflecting surfaces to guide the matches into the receiving notches 14 of the disks 10. The front and rear walls 3 and 4 of the casing have portions 14 which are inclined inwardly and which terminate beneath the deflecting surfaces 13 of the member 12 to assist in the function of the said surfaces toward providing a perfect

feed of the matches to the dispensing device.

The casing 1 is provided with a relatively heavy base 15 which is formed on its upper surface to provide a delivering trough or gutter 16, the wall 17 of which being inclined upwardly and rearwardly and extended directly into the wall 4 of the casing. The trough is located in advance of the terminal 18 of the wall 2 of the casing, and said terminal being associated with respect to the trough to form therefor a guide to direct the matches onto the wall 17 in other words the side walls of the groove are disposed substantially tangential to the shaft 8. The terminal 18 and the wall 17 define the match discharge passage 19, and as shown, said passage is located directly beneath the axis of the dispensing or delivering device. The member 12 is provided on its upper surface at the center with a relatively sharp dividing edge 20 which operates to split the batch of matches to cause parts of the batch to be moved toward the opposite sides of the casing. The notches 11 are substantially of dovetail configuration, so that each notch is of a gradually inwardly increasing diameter presenting retaining projections 11^a to hold the match against accidental escape from the notch on movement of the feeder to discharge the match and to guard the match against frictional contact with the walls of the casing to prevent the ignition thereof through frictional contact. In view thereof, the tendency of the match is to roll into the corners of the grooves so as to be held in the slots against any possible frictional engagement with the walls of the casing. The front of the base 15 is provided with a suitable match striking surface 21.

In the modified form of the invention shown in Fig. 3, the base shown in the preferred form is omitted, and in lieu thereof, the wall 22 is extended downwardly, at 23, and then outwardly, at 24, to provide a receiving trough 25, the portion 24 being provided with a striking surface 26. In this form of the invention, the casing carries a wall engaging bracket 27.

I claim:

A match box comprising a casing having a discharge opening therein, a feeder located in the casing and including a revolvably mounted shaft provided with a member

thereon having a peripheral groove therein of an inwardly increasing diameter so that the side walls of the groove lie substantially tangential to the shaft to permit the match to gravitate thereon to the lowermost corner of the groove whereby the match is held against accidental escape from the groove on movement of the feeder to discharge the match and to guard the match against fric-

tional contact with the walls of the casing 10 to prevent the ignition thereof through frictional contact with the walls.

In testimony whereof I affix my signature in presence of two witnesses.

FREDERICK C. HOLKUM.
